UNITED STATES PATENT OFFICE.

ALBERT F. JONES, OF SALEM, MASSACHUSETTS, ASSIGNOR TO AMERICAN GRANITE MACHINE COMPANY, OF SALEM, MASSACHUSETTS, A CORPORATION OF MAINE.

STONE-DRESSING MACHINE.

SPECIFICATION forming part of Letters Patent No. 741,582, dated October 13, 1903.

Application filed December 18, 1900. Serial No. 40,264. (No model.)

To all whom it may concern:

Be it known that I, ALBERT F. JONES, of Salem, county of Essex, State of Massachusetts, have invented an Improvement in Stone-Dressing Machines, of which the following description, in connection with the accompanying drawings, is a specification, like letters on the drawings representing like parts.

This invention has for its object to construct a stone-dressing machine especially adapted for roughing off the surface of a stone in such manner that the edges of the stone will not be chipped off during the operation; and the invention consists, essentially, in the combination of a cutter, means for moving it back and forth in a circular path, a platform bearing the stone, and feeding mechanism for said platform constructed and arranged to advance the stone in a direction from the axis toward the middle of the circular stroke of the cutter; also, in the combination of a cutter, means for moving it back and forth in a circular path, a platform bearing the stone, means for adjusting the stone relative to the cutter, whereby the axis of the circular stroke of the cutter will be disposed substantially midway between the opposite edges of the surface of the stone, and means for moving the platform to advance the stone against the cutter in a direction from the axis toward the middle of the circular stroke of the cutter; also, in other features, as will be hereinafter described.

In carrying out this invention a revoluble cutter is preferably employed, and said cutter is carried by an oscillating arm and is disposed relative thereto with its axis disposed slightly oblique to the axis of the arm. The cutter is adjustably mounted on said oscillating arm in such manner that the obliquity of its axis may be varied, and said cutter is also adjustably mounted on said arm in such manner that it may be disposed at varying distances from the axis of the arm. The arm is oscillated to carry the cutter in a circular path, thereby giving it a circular stroke or sweep, and in practice I prefer to so construct and arrange the parts that said arm travels a complete semicircle. As the cutter is adjusted toward and from the axis of the oscil-

lating arm the radius of its circular stroke will be varied. The stone to be cut is placed upon a platform and feeding mechanism is provided for moving said platform to advance the stone against the acting edge or portion of the cutter in a direction from the axis of the oscillating arm toward the middle of the circular stroke of the cutter. In adjusting the essential parts of the machine the stone will be set so that the axis of the oscillating arm will be disposed substantially midway between the opposite edges of the surface of the stone and the cutter will be adjusted on the arm at a proper distance from the axis of said arm, so that as the arm oscillates the acting edge or portion of the cutter will traverse the stone from edge to edge, moving in a circular path, and consequently making a circular cut, and as the stone is advanced by the feeding mechanism in a direction from the axis of the oscillating arm toward the middle of the circular stroke of the cutter the edges of the stone will not be chipped off by the cutter.

Figure 1 is a front elevation of a stone-dressing machine embodying this invention. Fig. 2 shows a plan view of the stone-dressing machine shown in Fig. 1. Fig. 3 is a side elevation of a portion of the machine, showing the revoluble cutter and oscillating arm bearing it and means for oscillating said arm. Fig. 4 is a side elevation of the mechanism for oscillating the arm which bears the revoluble cutter. Fig. 5 is a plan view of the platform upon which the stone is placed. Fig. 6 is an end view of said platform. Fig. 7 is a sectional detail of the revoluble cutter. Fig. 8 is a detail of the supporting-plate for the bearing-box of the cutter-carrying spindle. Fig. 9 is a longitudinal section of the shaft bearing the oscillating arm. Fig. 10 is a cross-sectional detail of the bearing-box. Fig. 11 is a diagram showing the manner of cutting the stone. Fig. 12 is a detail of the box containing the longitudinally - adjustable bushing supporting the shaft to which the cutter-carrying arm is attached.

The cutter *a* is herein shown as a disk of ordinary construction, and said cutter is adapted to be supported so as to revolve

freely. The means herein shown for thus supporting the cutter a consists of a cylindrical spindle a' , (see Fig. 7,) mounted to revolve freely in a box a^2 and having a hole through it through which passes a bolt a^3 , by means of which the disk a is secured to the spindle. The bolt a^3 has a nut a^{20} at one end and a head a^4 at the opposite end, and said head a^4 is made more or less conical or tapering, and the bolt-hole through the center of the cutter a is also made to correspondingly taper to receive the head a^4 . A washer a^5 is placed on the bolt a^3 , between the cutter a and the adjacent end of the spindle. When the nut a^{20} on the bolt is tightened, the cutter a will be securely held in position.

A roller-bearing is provided for resisting the end thrust of the cutter-carrying spindle a' , which, as herein shown, consists of a set or group of rollers a^6 contained in recesses in a ring or holder a^7 , which is disposed between two flat rings a^8 a^9 contained in the box a^2 , and the rearmost end of the spindle a' is cut away or reduced in diameter to receive said roller-bearing and also to form an abutting shoulder against which the ring a^9 bears. The rearmost end of the bearing-box a^2 is closed by an end piece or circular plate a^{10} , which is bolted or otherwise secured to the box.

30 The bearing-box a^2 is adjustably mounted on a plate b to turn on an axis at right angles to the axis of rotation of the cutter-carrying spindle a' , and, as herein shown, said plate b is made as a segment of a circle, (see Fig. 8,) 35 having a downwardly-projecting ear b' , which is adapted to be bolted or otherwise secured to an arm c . The plate b has a central stud b^2 rising from it, which serves as a pivot for the bearing-box.

40 The bearing-box a^2 has projecting from each side of it a thin web or flange a^{12} , through which curved slots a^{13} are cut or formed, and bolts a^{15} pass through said curved slots a^{13} and through any one of a series of holes b^3 in the plate b to thereby secure the bearing-box a^2 to said plate b . The holes b^3 in said plate b are arranged in a circle concentric to the pivot-stud. By loosening the bolts a^{15} the bearing-box a^2 may be turned on the pivot-stud as a center and adjusted more or less within the limitations of the slots a^{13} , and if further adjustment is required said bolts a^{15} may be removed and replaced in other holes b^3 in the plate b . The bolt b^7 , which passes 55 through the ear b' , also passes through a slot in the arm c , (see Fig. 4,) thereby providing for adjustment of the plate b along on said arm c toward and from the axis of the arm. A clamping-plate b^4 is secured to the under 60 side of said plate b by a bolt b^9 , which is formed with a projection b^5 , which passes beneath the arm c , and said clamping-plate serves to assist in holding the plate b on the arm.

65 The cutter-carrying arm c is herein shown as a bar of angle-iron projecting from a hub c' , and said hub c' is secured to one end of a

horizontal shaft d , which is supported by a suitable bushing d' , contained in a box d^2 , which is secured to the framework. The hub c' of the cutter-carrying arm is splined onto said shaft d , and said hub has a counterbalance d^{20} for the arm secured to it. The cylindrical bushing d' , containing said shaft d , is contained in the box d^2 , which is bolted or otherwise secured to the frame, and said box d^2 has an elongated opening d^3 in one side of it, through which a finger d^4 projects, and said finger has a slot d^5 at or near its outer end, through which a bolt d^6 passes, which connects said finger rigidly to a lip d^7 , which is located at one side of the opening d^3 . The bushing is thus rigidly held by the bolt d^6 against longitudinal movement, yet by loosening said bolt said bushing may be adjusted 85 longitudinally within the limitations of the slot d^5 . The lip d^7 has a number of holes d^8 , any one of which may receive the bolt d^6 , thereby providing for greater longitudinal adjustment of the bushing than can be obtained by the slot d^5 . As the bushing is thus adjusted longitudinally the oscillating cutter-carrying arm c is bodily moved with it and the cutter thereby moved toward and from the work.

95 The shaft d has secured to it a toothed wheel e , which engages a pinion e' , secured to a shaft e^2 , to which a toothed wheel e^3 is secured, which engages a pinion e^4 , secured to a shaft e^5 , bearing a fast pulley e^6 and two loose pulleys e^7 e^8 , said loose pulleys being located one at each side of said fast pulley. Two belts e^9 e^{10} are provided, one of which, as e^{10} , will be a crossed belt, and means are provided for moving said belts simultaneously on the pulleys, so that either one of them may be moved into engagement with the fast pulley e^6 , and as one of said belts is crossed said fast pulley will be rotated in one or the other direction and in turn through 110 the gearing above described will oscillate the shaft d , bearing the cutter-carrying arm. The means herein shown for thus simultaneously moving the belts consists of a rod or bar f , having two belt-receiving eyes f' f^2 projecting laterally from it in opposite ways, and a swinging arm f^3 , to the extremity of which said rod or bar f is attached, and means for swinging said arm f^3 . The arm f^3 is secured to the upper end of a vertical rod or bar f^4 , having its bearings in a bracket f^5 on the frame, and an arm f^6 is secured to the lower end of said rod or bar f^4 , which has a stud f^7 (see dotted lines, Fig. 4) projecting from it. The stud f^7 enters a cam-groove formed in the under side of a plate f^8 , secured to the lower end of an arm f^9 , pivoted at f^{10} and forming one arm or member of a bell-crank lever, the other arm or member, f^{12} , of said bell-crank lever projecting at substantially 125 right angles to the arm f^9 and made long enough to enter the path of movement of two dogs f^{14} f^{15} , which are secured to the shaft d and project therefrom radially in different

directions. The dogs $f^{14} f^{15}$ are adjustably secured to said shaft d , so as to be independently moved around the shaft to occupy different relative positions. When the fast pulley e^6 is driven in one direction by the gearing aforesaid, the shaft d will be turned until one of said fingers strikes the arm f^{12} , when the bell-crank lever will be moved on its pivot, and the cam-grooved plate f^7 moving with said bell-crank lever will swing the arm f^6 , and thereby swing the arm f^3 and move the rod or bar f and move the belts, and the fast pulley will then be caused to rotate in the opposite direction and will continue to thus rotate until the other dog on the shaft d strikes the arm f^{12} of the bell-crank lever.

g represents a platform, which will be made of any suitable construction adapted to receive the stone, and, as herein shown, said platform has on its under side a number of supports g' , arranged in two parallel rows, each support being grooved or recessed to rest upon and slide along on a pair of rods or bars g^2 , suitably supported on upright stands g^3 , erected on a base g^4 , the lower grooved or recessed ends of the supports g' having their extremities turned under the guide rods or bars g^2 , so as to effectively hold the platform from rising, which it would be liable to do even with the stone on the platform, while the cutter is cutting the stone on its upward stroke. The platform is movable and from by means of a feed-screw g^5 , which passes through suitable threaded ears g^6 (see dotted lines, Fig. 6) projecting from the under side of the platform. A toothed wheel i is secured to said feed-screw g^5 , which engages a pinion i' located beneath it and secured to a shaft to which a toothed wheel i^2 is secured, and said toothed wheel i^2 engages a pinion i^3 , secured to a shaft bearing a bevel-gear i^4 , which is engaged and driven by a bevel-gear i^5 , secured to a shaft i^6 . It is designed that the feed-screw shall be rotated constantly while the machine is in operation.

The platform g has erected upon it a number of stone-retaining devices consisting of an upright frame m , having a roller-supporting portion m' adjustably connected to it. The upright stands are rigidly secured to the platform g or they may be adjustably secured thereto, and as herein shown the stands at one end of the platform are rigidly secured to the platform, while the stands at the opposite ends and along one side of the platform are adjustably secured thereto, occupying positions in guideways provided for them. Cross-bars n are provided, (see Figs. 5 and 6), which are adapted to be placed on the platform g , each having a number of jack-screws n' , upon which the stone or other like cross-bars may rest. By means of these cross-bars and jack-screws the stone may be elevated to any predetermined position. Thus, as it is herein desired to support the stone at a pre-

determined elevation, these cross-bars or some equivalent form of adjusting device becomes necessary. I do not, however, desire to limit my invention to the employment of any particular means for adjusting the stone to a predetermined elevation.

The stone to be cut will be placed on the platform and adjusted to an elevation where by the axis of the oscillating shaft d will be disposed approximately midway between the upper and lower edges of the stone, and when thus located relative to said shaft the cutter will be adjusted on the arm, so that the diameter of its circular stroke will be approximately equal to the width of the stone. It will be observed that by thus cutting the stone the edges will not be chipped off, as the cutter does not act with an outward thrust at the edge.

In Fig. 11 a diagram is shown which is intended to illustrate my method of cutting stone by the machine forming the subject-matter of this application, whereby the edges will not be chipped off. When the stone has been placed on the platform and properly positioned relative to the cutter and the cutter properly adjusted on its arm, the stone will be constantly fed toward the cutter in a direction from the axis of the oscillating shaft d toward the middle of the circular stroke of the cutter.

It is obvious that many of the details of construction of the machine herein shown may be changed without departing from the spirit and scope of my invention.

I claim—

1. In a stone-dressing machine, the combination of a swinging arm, a cutter borne by it disposed with its cutting edge directed toward the axis of the arm, an oscillating shaft to which said arm is secured, means for oscillating said shaft, a platform bearing the stone and feeding mechanism for said platform constructed and arranged to advance the stone against the cutter in a direction from the axis of the shaft toward the extremity of the arm, substantially as described.

2. In a stone-dressing machine, the combination of a swinging arm, a cutter borne by it disposed with its cutting edge directed toward the axis of the arm, a bearing-box for said cutter, means for adjusting said box on the arm to vary the angle of the cutter, an oscillating shaft to which said arm is secured, means for oscillating said shaft, a platform bearing the stone and feeding mechanism for said platform, constructed and arranged to advance the stone against the cutter in a direction from the axis of the shaft toward the extremity of the arm, substantially as described.

3. In a stone-dressing machine, the combination of a swinging arm, a cutter borne by it disposed with its cutting edge directed toward the axis of the arm, a bearing-box for said cutter, means for adjusting said bearing-box toward and from the extremity of said

4
arm, an oscillating shaft to which said arm is secured, means for oscillating said shaft, a platform bearing the stone and feeding mechanism for said platform, constructed and arranged to advance the stone against the cutter in a direction from the axis of said shaft toward the extremity of the arm, substantially as described.

5. In a stone-dressing machine, the combination of a cutter, a bearing-box therefor, an arm carrying said bearing-box, means for adjusting said box on the arm to vary the angle of the cutter, means for adjusting said bearing-box toward and from the extremity of said arm, an oscillating shaft to which said arm is secured, means for oscillating said shaft, a platform bearing the stone and feeding mechanism for said platform, constructed and arranged to advance the stone against the cutter in a direction from the axis of the shaft toward the extremity of the arm, substantially as described.

6. In a stone-dressing machine, the combination of a cutter movable back and forth in a circular path, a support for holding it with its cutting edge directed toward the axis of its path of movement, means for moving said cutter, a platform bearing the stone, and feeding mechanism for moving said platform in a direction from the axis toward the middle of the circular stroke of the cutter, substantially as described.

7. In a stone-dressing machine, the combination of a cutter movable back and forth in a circular path, a support for holding the cutter with its cutting edge directed toward the axis of its path of movement, means for moving the cutter, a platform bearing the stone, and feeding mechanism for said platform operating at the same time the cutter is moving, for moving said platform in a direction from the axis toward the middle of the circular stroke of the cutter, substantially as described.

8. In a stone-dressing machine, the combination of a swinging arm, a cutter borne by it disposed with its cutting edge directed toward the axis of the arm, an oscillating shaft to which said arm is secured, means for oscillating said shaft, a platform on which the stone is placed, means for adjusting the stone relative to the cutter to bring its opposite edges within the chord of the arc of movement of the cutter, and feeding mechanism

for moving said platform in a direction from the axis of said shaft toward the middle of the circular stroke of the cutter, substantially as described.

9. In a stone-dressing machine, the combination of a cutter, a bearing-box therefor, an arm carrying said bearing-box, means for adjusting said box on the arm to vary the angle of the cutter, an oscillating shaft to which said arm is secured, means for oscillating said shaft, a platform on which the stone is placed, means for adjusting the stone relative to the cutter to bring its opposite edges within the chord of the arc of movement of the cutter, and feeding mechanism for moving said platform in a direction from the axis of said shaft toward the middle of the circular stroke of the cutter, substantially as described.

10. In a stone-dressing machine, the combination of a cutter, a bearing-box therefor, an arm carrying said bearing-box, means for adjusting said bearing-box toward and from the extremity of said arm, an oscillating shaft to which said arm is secured, means for oscillating said shaft, a platform on which the stone is placed, means for adjusting the stone relative to the cutter to bring its opposite edges within the chord of the arc of movement of the cutter, and feeding mechanism for moving said platform in a direction from the axis of said arm toward the middle of the circular stroke of the cutter, substantially as described.

11. In a stone-dressing machine, the combination of a cutter, a bearing-box therefor, an arm carrying said bearing-box, means for adjusting said box on the arm to vary the angle of the cutter, means for adjusting said bearing-box toward and from the extremity of said arm, an oscillating shaft to which said arm is secured, means for oscillating said shaft, a platform on which the stone is placed, means for adjusting the stone relative to the cutter to bring its opposite edges within the chord of the arc of movement of the cutter, and feeding mechanism for moving said platform in a direction from the axis of said arm toward the middle of the circular stroke of the cutter, substantially as described.

12. In a stone-dressing machine, the combination of a cutter-carrying arm bearing a cutter, an oscillating shaft to which said arm is secured, means for oscillating said shaft, means for adjusting said shaft longitudinally, a platform on which the stone is placed, means for adjusting the stone relative to the cutter to bring its opposite edges within the chord of the arc of movement of the cutter, and feeding mechanism for moving said platform in a direction from the axis of said shaft toward the middle of the circular stroke of the cutter, substantially as described.

13. In a stone-dressing machine, the combination of a cutter-carrying arm bearing a cutter, an oscillating shaft to which said arm is secured, a bushing in which said shaft is free

to oscillate, a lateral projection on said bushing, a box containing said bushing having a side opening for said lateral projection and having a lip to which said projection is secured, substantially as described.

14. In a stone-dressing machine, the combination of a swinging cutter-carrying arm, a cutter borne by it disposed with its cutting edge directed toward the axis of the arm,

15 means for swinging said arm to move the cutter in a circular path, a platform bearing the stone, means for adjusting the stone relative to the cutter to bring its opposite edges within the chord of the arc of movement of the cutter, and means for moving the platform in a direction from the axis on which the cutter-carrying arm swings toward the middle of the circular stroke of the cutter, substantially as described.

16 15. In a stone-dressing machine, the combination of a swinging arm, a cutter borne by it disposed with its cutting edge directed toward the axis of the arm, an oscillating shaft to which said arm is secured, means for oscillating said shaft, a platform bearing the stone, stone-retaining devices thereon, guideways on which said platform moves, means for holding said platform in position on said guideways yet permitting it to be moved

25 30 along, and means for moving said platform on said guideways, substantially as described.

16. In a stone-dressing machine, the combination of a swinging arm, a cutter borne by it disposed with its cutting edge directed to-

ward the axis of the arm, an oscillating shaft 35 to which said arm is secured, means for oscillating said shaft to thereby swing the cutter-carrying arm in a vertical plane, a platform bearing the stone, stone-retaining devices thereon, guideways on which said platform moves, means for holding said platform in position on said guideways yet permitting it to be moved along, and means for moving said platform on said guideways, substantially as described.

17. In a stone-dressing machine, the combination of a swinging arm, a cutter borne by it, disposed with its cutting edge toward the axis of the arm, a platform bearing the stone, stone-retaining devices thereon, guideways on 50 which said platform moves, means for holding said platform in position on said guideways yet permitting it to be moved along, means for adjusting the stone relative to the cutter to bring its opposite edges within the 55 chord of the arc of movement of the cutter, and means for moving the platform in a direction from the axis toward the middle of the circular stroke of the cutter, substantially as described.

In testimony whereof I have signed my name to this specification in the presence of two subscribing witnesses.

ALBERT F. JONES.
